UNITED STATES PATENT OFFICE

103,254

DESIGN FOR A CURLER OR SIMILAR ARTICLE

Marie C. Steichen, West Englewood, N. J.

Application June 1, 1935, Serial No. 57,087

Term of patent 3½ years

To all whom it may concern:

Be it known that I, Marie C. Steichen, a citizen of the United States, residing at West Englewood, county of Bergen, State of New Jersey, have invented a new, original, and ornamental Design for a Curler or Similar Article, of which the following is a specification, reference being had to the accompanying drawing, forming part thereof.

The figure is a perspective view of the curler or similar article showing the new design.

I claim:

The ornamental design for a curler or similar article, substantially as shown.

MARIE C. STEICHEN.
